UNITED STATES PATENT OFFICE.

GUSTAVOS HEIDEL AND ISAAC E. REIS, OF ST. LOUIS, MISSOURI, ASSIGNORS
TO THE MISSOURI NOVELTY WORKS, OF SAME PLACE.

SAD-IRON.

SPECIFICATION forming part of Letters Patent No. 533,805, dated February 5, 1895.

Application filed November 27, 1893. Serial No. 492,124. (No model.)

To all whom it may concern:

Be it known that we, GUSTAVOS HEIDEL and ISAAC E. REIS, of the city of St. Louis, in the State of Missouri, have invented a certain new and useful Improvement in Sad-Irons, of which the following is a full, clear, and exact description, reference being had to the accompanying drawings, forming part of this specification.

Our invention relates to certain improvements in sad or smoothing irons, and which is adapted to all kinds of such articles, such as family irons, tailor irons, and "goose" irons; and our present invention relates to an improvement upon the iron shown and described in Patent No. 454,820, issued June 23, 1891, to Gustavos Heidel and Mary T. Reis.

Our present invention consists in features of novelty hereinafter fully described and pointed out in the claim.

Figure I is a side elevation of our improved iron. Fig. II is a horizontal section, taken on line II—II, Fig. I. Fig. III is a transverse, vertical section, taken on line III—III, Fig. I. Fig. IV is a detail, vertical section, taken on line IV—IV, Fig. III. Fig. V is a side elevation illustrating the iron with an open handle.

Referring to the drawings, 1 represents the body portion of the iron, and 2 the handle portion, the latter consisting of a plate 3, having standards 4, to which is secured the handle 5.

On the upper face of the body portion 1 are parallel lugs or projections 6 at the sides of the iron, near the middle. These lugs or projections are under-cut, as shown at 7, Fig. III. At the front end, and on top of the body portion is a lug or projection 8, having a V-notch, as shown in Fig. II. In the upper face of the body portion between the lugs 6, is an elongated recess or cavity 9 formed with tapering sides. On the under side of the plate 3 are parallel lugs or projections 10, which flare outwardly, as shown in Fig. III and which are adapted to fit between the projections or lugs 6 of the body; the lugs 6 and 10 forming a loose dove-tail joint between the plate and the body portion of the iron. On the under side of the plate 3 is also a projection 11, near the front end of the plate. This projection 11, as shown in Fig. II, is V-shaped

so as to fit into the V-shaped notch in the projection 8. On the rear or back end of the plate 3 are legs or projections 12, which fit or bear upon the upper surface of the body portion 1, 55 when the handle portion is in place.

13 represents a perforation in the plate 3, near its middle, through which passes the non-circular shank 14 of a block 15 having vertical sides, the shank having a head 16 on 60 its upper end, by which it may be raised. When the handle portion of the iron is in place it will be seen that the tapering sides of the cavity permit of the block 15 seating itself centrally therein, while at the same 65 time the tapering rear wall forces the handle plate forward keeping the V-shaped projection 11 in engagement with the lug 8. This construction prevents any lateral or longitudinal movement of the handle plate during 70 the working of the iron. This construction also prevents any binding between the side lugs on the handle plate and body of the iron and thus avoids any danger of the said parts sticking.

To couple the two parts of the iron, the handle portion is placed over the body portion, with the lugs or projections 10 back of the lugs or projections 6. The handle portion is then pressed forwardly, causing the projections 10 to enter between the projections 6, and when the projection 11 seats in the recess of the projection 8, the block 15 will drop into the recess 9, and hold the two parts of the iron together until the block is raised 85 again, the legs 12 serving to support and steady the rear part of the handle portion on the body portion.

The advantage of this construction over that shown in the patent referred to, is that 90 there are no tight joints between the projections on the handle portion, and the projections on the body portion, which are liable to stick, on account of the heating of the iron. The projection 11 and the block 15 prevent 95 the forward and lateral movement of the handle portion with relation to the body portion when the parts are connected, while the block 15 prevents the rearward movement of the handle portion with relation to the body portion, and the lugs 6 and 10 are only utilized 100 for the purpose of preventing the vertical

movement of the handle portion with relation to the body portion, for which purpose it is not necessary to have a tight or close fit between the lugs, but a loose fit is sufficient, as shown in Fig. III, and thus when the iron is heated there is no tendency of the handle portion to be stuck to the body portion, as was found to be the case in the patent mentioned, and the block 15 may be a mere drop-lock instead of having a threaded connection with the handle portion, as shown in said patent.

In Fig. V we have shown one arm 4, of the handle portion removed, to better suit the iron for tailors' use.

We claim as our invention—

In a sad iron, a body portion having parallel side lugs 6 inclined inwardly, and a front lug having a V-notch, a handle portion having a plate provided on its under side with

legs 12, parallel side lugs 10 inclined outwardly, and a V-shaped lug 11, adapted to fit into the V-notch in the front lug on the body portion and a block 15 having vertical sides and a stem passing through the plate, said block being adapted to fit in a cavity in the body portion formed with tapering sides and to force the V-shaped lug 11 into engagement with the V-notch in the front lug, whereby any lateral or longitudinal movement of the plate with relation to the body portion during the working of the iron and any binding between the side lugs is prevented, substantially as shown and described and for the purpose set forth.

GUSTAVOS HEIDEL.
ISAAC E. REIS.
